FOREIGN PATENT DOCUMENTS

JP D1639032 * 7/2019

Primary Examiner — Paula Allen Greene(74) *Attorney, Agent, or Firm* — Banner & Witcoff, Ltd.(57) **CLAIM**

The ornamental design for a headphone, as shown and described.

DESCRIPTION

FIG. 1 is a front top perspective view of a headphone showing our new design in a first position;

FIG. 2 is a front bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front top perspective view of the headphone in FIGS. 1-8 shown in a second position.

The broken lines depict portions of the headphone that form no part of the claimed design.
